UNITED STATES PATENT OFFICE.

WILLIAM LOUDEN, OF FAIRFIELD, IOWA.

DOOR-HANGER.

SPECIFICATION forming part of Letters Patent No. 707,853, dated August 26, 1902.

Application filed January 13, 1902. Serial No. 89,588. (No model.)

To all whom it may concern:

Be it known that I, WILLIAM LOUDEN, a citizen of the United States, residing at Fairfield, in the county of Jefferson and State of Iowa, 5 have invented a new and useful Improvement in Door-Hangers, of which the following is a specification.

My invention relates to door-hangers having a frame carrying a rotary wheel to run 10 on an overhead track, said frame being adapted to be pivotally connected to a door; and it consists, first, in an adjustment of parts whereby the door will tend to move laterally 15 toward the wall to which it is applied, thus insuring a close fit, while at the same time it will be free to be moved away from the wall to pass obstructions thereon.

It consists, further, of improvements in the details of construction which are hereinafter 20 set forth, and more particularly pointed out in the claims.

In the accompanying drawings, Figure 1 is an elevation of a door and wall of a building 25 with a hanger and track embodying my invention applied thereto, the door and wall being broken away. Fig. 2 is a perspective of the hanger detached from the door. Fig. 3 is a vertical section of the door and hanger as applied to the wall. Fig. 4 is the same, 30 showing the door pushed laterally away from the wall. Fig. 5 is a perspective of an improved form of the lower frame. Fig. 6 is a perspective of one of the brackets which secures the track to the wall. Fig. 7 is a detail view.

Referring to the drawings, A represents the track-rail, and B the brackets which secure it to the wall W. The hangers which support the door D are composed of two sections 40 C and E, having jointed connections F. The upper part of the hanger-frame C has a grooved track-wheel G, which is mounted between cheek-pieces I and J in the usual manner, the cheek-piece I being made integral with the frame C and the cheek-piece J being riveted at its ends to the cheek-piece I. In the lower corners of the frame C are rectangular-shaped loops H. The lower part of the section E is made U-shaped or V-shaped, as desired. Its 45 upper ends are recurved or formed with hooks which are adapted to pass through the loops H and catch on the pivots F and swing there- 50 on. As shown in Figs. 2, 3, and 4, these recurved ends are extended downwardly and laterally, so as to embrace the upper end of the 55 door D, and are perforated to receive bolts K. Another perforation is made in the lower end of the part E to receive the bolt M.

One of the essential features is the location 60 of the pivot F, and another is the arrangement of the wheel-carriage C so that it and the wheel G will be free to oscillate to a considerable extent on the track-rail A or to assume an angular position relatively to the vertical. As heretofore constructed this 65 pivot or hinge has been placed either immediately below the vertical center of the wheel G and track-rail A or a considerable distance to one side, with the wheel held in a practically rigid vertical position. When the hinge 70 is located immediately below the central line of the wheel and track-rail, the door is disposed to hang tremulously, and the frame E is easily vibrated by the wind blowing against the door, and it will not be held steadily in 75 contact with the wall. Also the upper edge of the wheel G while in its normal vertical position will be only a short distance from the upper end of the bracket B and the wall W, to which it is attached. Therefore when 80 the door is pushed away from the wall by the warping of the timbers or otherwise its lateral movement will be limited by the upper edge of the wheel coming in contact with the wall or bracket. On the other hand, when the 85 hinge is placed a considerable distance to the outside of the wheel G the wheel-carriage C, if left free to oscillate, will be thrown so far 90 out of vertical alinement that special rollers or guides will be required to keep it in operable position, and these rollers or guides will greatly lessen, if they do not entirely prevent, the necessary lateral movement of the door. In order to overcome these defects and give 95 the door the largest amount of lateral movement when required and at the same time hold it with sufficient contact against the wall to insure its closely fitting the wall, I have located my hinge or joint out of alinement with the point of support of the wheel upon 100 the track and preferably on a direct line with the outer side of the wheel G, as shown by the dotted lines X X in Figs. 3 and 4, and have constructed the wheel-carriage so the

wheel will be free to oscillate to a considerable extent on the upper edge of the track-rail A or to assume an angular position, as is also shown by Figs. 3 and 4. This brings 5 the pivot F somewhat outside of the vertical center of the wheel G and track-rail A, and the weight of the door will cause it to swing inwardly toward the wall W. This will naturally throw the upper edge of the wheel G 10 outwardly, as shown in Fig. 3, which will be its normal position as long as the door is free to assume a normal position; but should the door be interfered with by inequalities of the wall or by its own inequalities coming in 15 contact with the wall it will be free to assume the position shown in Fig. 4 or any intermediate position, in which case the pivot F will be swung outwardly and the upper edge of the wheel G will be thrown inwardly 20 toward the wall. Of course the door will retain this position only as long as it is held there by the wall or some other interfering obstacle, and as soon as this is removed it will swing back to its normal position, as 25 shown in Fig. 3. This always insures a close fit of the door against the wall and at the same time permits the door to move freely outwardly to a considerable extent to escape any obstruction with which it may come in 30 contact. When the style of hanger shown in the drawings is used, it is preferable that the track should be rigidly secured to the wall and that the frame C shall oscillate on the track; but I do not confine myself to this 35 alone. Any form of hanger and track may be used which will support the door out of line with the center of gravity laterally and which will leave it free to move laterally, whereby the door will tend to hug the side 40 of the wall to which it is applied. To provide for the largest amount of lateral movement, the opening between the lower part of the frame C and the ordinary guide-lug L should be made wider than usual, as shown 45 in Figs. 3 and 4. It is also advisable to put a strip of wood N on the inner side of the batten O at the upper edge of the door next to the wall, so as to slide thereon, and this helps to shut out the wind and storm, and 50 may be called a "weather-strip." It will be seen that by this arrangement a close-fitting door will always be secured with enough elasticity in its hangings to let it readily accommodate itself to the inequalities of the wall, 55 and, further, that no extra guides or rollers will be required to hold the frame C in operable position.

Fig. 5 is an improved form of the lower section or strap E, which to distinguish it 60 from the other is lettered E'. This strap E' is designed to fit any thickness of door and is applied only to the outer side thereof. Its upper ends are set over to the proper place to connect with the pivot F and are provided 65 with hooked ends O to catch thereon. These ends can be left open, as shown in Fig. 5, or after they are hooked over the pivots F they

may be closed, so as to prevent the sections from coming apart. The lower ends of the strap E' are made V-shaped, and perforations 70 are made in the upper and lower ends of the V for the admission of bolts to attach the strap to the door. Strengthening-webs P are also formed thereon to give greater rigidity to the strap. The straps E and E' being each 75 made integral or rigidly joined together at their lower ends are adapted to more thoroughly brace the lower corners of the frame C, to which they are hinged, than if they were made in two separate pieces, and to add to 80 this solidity in the improved form E', I have added a horizontally-disposed brace Q, which connects its upper ends together, and, if desired, a perforation R may be made in the 85 central portion of this brace for the admission of a bolt to assist in holding the strap more securely to the door.

Fig. 6 is a perspective of one of the brackets used to hold the track-rail A to the wall W. It is made L-shaped, with its vertical portion 90 adapted to rest against the wall and its horizontal portion to extend out to and support the track-rail. Its upper end is rounded, and the transverse edges of the rounded ends are rounded off, and it is fitted with an eye S for the 95 reception of a screw or bolt or for a staple T, as shown in Fig. 6. The central part of both the vertical and horizontal portions of the bracket is recessed or made thinner than the ends and is fitted with perforations U for the 100 reception of screws, while the edges are fitted with flanges V, which extend from the end containing the eye S to the end Y, which is riveted into the track-rail A, but being widest and strongest at the point where the vertical 105 and horizontal portions are joined together. By this construction the greatest strength and lightness and consequent cheapness are secured and the bracket may be connected to the wall by the staple T or its equivalent 110 alone, so that it may freely swing out from the wall, if desired, or it may be rigidly secured thereto by screws, as shown in Fig. 1.

Fig. 7 is a vertical section on the line 7 7 of Fig. 2 and shows the manner of securing 115 the cheek-pieces I and J together. These cheek-pieces after passing by the wheel G are inwardly contracted, so as to fit against each other, and the piece J is riveted to the piece I, as shown in the figure. Below the rivet 120 which secures the pieces together their ends Z are spread apart, so as to straddle the upper edge of the track-rail A, a portion of which is also shown in the figure. The ends of the pieces I and J being inclined, as shown in 125 Fig. 2, and being extended down and spread apart, so as to straddle the upper edge of the rail, will run under and throw obstructions off the track, as will be readily understood, and at the same time the piece J will 130 be securely held in place by its contact with the piece I. The straps E and E' instead of being made in the shape of a U or V may be made in any other desired form, provided

their lower ends are joined together so as to form one rigidly-connected part, so as to securely brace the looped corners of the frame C, substantially as described.

5 What I claim is—

1. In a door-hanger, the combination with a suitable track, of a hanger-frame carrying a rotary wheel mounted on said track and pivotally secured to a door, the pivotal points of support being laterally out of line with the line of the center of gravity, whereby the lower portion of said frame is free to move toward said line of gravity or to be moved therefrom and the door will tend to move laterally 15 toward said point of support, substantially as described.

2. The combination with a suitable track, of a door-hanger comprising two sections having a jointed or pivotal connection between them, the upper section carrying a track-wheel adapted to run upon said track, and the lower section adapted to be secured to a door; said upper section being free to assume an angular position relatively to the vertical, and 25 the joint or pivot between the sections being located so that the center of gravity will be out of line with the point of support, whereby the door will tend to move laterally, said lateral movement being facilitated by the angular movement of the upper section.

3. The combination with a track adapted to be secured to a wall, of a door-hanger consisting of two sections having a jointed or pivotal connection between them, the upper section carrying a track-wheel and being adapted to oscillate laterally upon said track, and the lower section being adapted to be secured to a door; said joint or pivot being situated to one side of the point of support of the wheel 35 upon the track whereby the door will tend to move laterally, said lateral movement being facilitated by the oscillation of the upper section upon the track.

4. The combination with a track adapted to be secured to a wall, of a door-hanger comprising two sections having a jointed or pivotal connection between them, the upper section carrying a track-wheel adapted to run centrally on said track and to oscillate laterally thereon, and the lower section being adapted 45 to be secured to a door; said joint or pivot being located on a line with one side of said wheel, whereby the door will tend to move laterally, substantially as described.

5. A door-hanger consisting of two separate 50 sections hinged together, the upper section carrying a track-wheel and having a rectangular-shaped loop on each of its lower corners set more or less outside of the periphery of said wheel, and the lower section being 55 adapted to be secured to a door and having hooks or recurved ends on its upper corners adapted to hook into said loops and swing on the pivots formed thereby.

6. In door - hangers a track - supporting 60 bracket being L-shaped in its general contour, and having its upper end thickened and rounded off both longitudinally and laterally and fitted with an eye, and its central portions recessed and perforated, its edges fitted 70 with strengthening-flanges, and its lower end flattened, thickened and shouldered, substantially as described.

7. In door-hangers a frame carrying a track-wheel to run on a track-rail, and having cheek-pieces to support the wheel, the ends of said cheek-pieces being contracted so as to fit together, and having lower extensions which are spread apart and adapted to straddle the track-rail, substantially as described. 80

Signed at Fairfield, Iowa, January 4, 1902.
